UNITED STATES PATENT OFFICE.

FRANK KILBERG AND WILLIAM LEV, OF DETROIT, MICHIGAN.

HORSESHOE.

1,184,352.

Specification of Letters Patent. Patented May 23, 1916.

Application filed January 27, 1916. Serial No. 74,538.

To all whom it may concern:

Be it known that we, FRANK KILBERG and WILLIAM LEV, citizens of the United States of America, residing at Detroit, in the 5 county of Wayne and State of Michigan, have invented certain new and useful Improvements in Horseshoes, of which the following is a specification, reference being had therein to the accompanying drawings.

10 This invention relates to horseshoes, and the primary object of our invention is to provide a shoe which may be easily and quickly attached to a horse's foot, without the use of nails. This object is attained by 15 providing a horseshoe with adjustable side clamps for engaging the sides of the hoof to coöperate with the toe piece of the shoe in firmly holding the shoe upon the hoof.

A further object of our invention is to 20 provide a horseshoe fastening means wherein the parts are constructed with a view to reducing the cost of manufacture and at the same time retain those features by which safety, durability, and simplicity of construction are secured, and with such ends in view, our invention resides in the novel construction to be hereinafter specifically described and then claimed.

Reference will now be had to the drawings, wherein—

Figure 1 is a perspective view of a horse-shoe in accordance with our invention; Fig. 2 is a cross sectional view of a portion of the same, illustrating one of the adjustable 35 side clamps; Fig. 3 is a cross-sectional view of the toe portion of the shoe; Fig. 4 illustrates views of a calk that may be used in connection with a shoe, and Fig. 5 is a side elevation of the shoe as applied to a hoof.

40 In the drawing, 1 denotes a flat horseshoe-shaped metallic bar devoid of the usual nail openings and grooves. The toe portion of the horseshoe has the outer edge thereof provided with an integral upwardly projecting 45 and inwardly inclined toe piece 2 for embracing the toe portion of a hoof.

The heel portions of the shoe have depending transverse enlargements 3 provided with transverse openings 4 to receive the flat 50 shanks 5 of side clamps 6. The shanks 5 have a series of openings 7 and said shanks

are held in the enlargements 3 by set-screws 8 or other fastening means.

The side clamps 6 have a cross-sectional shape corresponding to that of the toe piece 55 2 and said side clamps and the toe piece 2 may be provided with screws 9, which may be screwed into the walls of a hoof, after the shoe has been clamped thereon to coöperate with the side clamps in positively holding 60 the shoe upon the hoof. In some instances, however, the screws 9 may be dispensed with.

The horseshoe 1 may be provided with the usual form of toe and shoe calks, but in Fig. 65 4 there is illustrated a preferred form of detachable calk 10 having a threaded stem 11 screwed into the bottom side of the shoe 1.

It is thought that the manner of placing the shoe in engagement with a hoof and its 70 utility thereon will be apparent without further description, and while in the drawings there are illustrated the preferred embodiment of my invention, it is to be understood that the structural elements are susceptible to such variations and modifications 75 as fall within the scope of the appended claim.

What we claim is:—

The combination in a horseshoe, of an inwardly inclined toe piece integral with the greater portion of the outer edge of said horseshoe, depending entanglements at the heel portions of said horseshoe and provided with transverse openings, said clamps at the heel 80 portions of said horseshoe as a continuation of said toe piece and movable to and from the outer edges of the heel portions of the shoe, shanks carried by said side clamps extending through the transverse openings in the enlargements of the horseshoe, and screws extending upwardly into the enlargements of the heel portions of said shoe and through the shanks of said side clamps to hold said side clamps in an adjusted position. 90

95 In testimony whereof we affix our signatures in presence of two witnesses.

FRANK KILBERG.
WILLIAM LEV.
